UNITED STATES PATENT OFFICE.

ALBERT F. EELLS, OF ROCHESTER, NEW YORK.

ANCHOR.

1,327,201.

Specification of Letters Patent.

Patented Jan. 6, 1920.

Application filed March 12, 1917. Serial No. 154,212.

To all whom it may concern:

Be it known that I, ALBERT F. EELLS, a citizen of the United States, residing at Rochester, in the county of Monroe and 5 State of New York, have invented certain new and useful Improvements in Anchors, of which the following is a specification.

This invention relates to certain new and useful improvements in anchors and it has 10 for its objects among others to provide an anchor of great strength, with minimum weight, with long flukes and so constructed that when dragged through the sea bottom its motion will cause the flukes to maintain a horizontal position and to automatically assume such position. It has for a further object to so construct the anchor and its flukes as to cause the same to cut deeper into the sea bottom. I place a cutting edge or cutting edges on the head connecting the two flukes and between which the shank is pivoted. I perforate the head of the anchor so as to offer as little resistance as possible to the passage of the water 15 20 25 so as to reduce the retardation of the ship when being driven into a heavy sea.

It has for a further object to so construct the head and flukes as to prevent fouling by the cable being wound around it, and also 30 to mount the shank of the anchor in the head in such a manner that it can be easily removed in case of damage to any part of the anchor, and easily replaced. I also provide sufficient space between the shank and 35 the flukes to prevent freezing or clogging. Further I form the flukes of a shape which embodies great strength in addition to giving them a tendency to always seek the horizontal position, thus insuring the deep bedding of the anchor without tendency to tilt or to be pulled or to roll out of the sea bottom.

On each side of the opening in which the shank is received, and at the inner sides of 40 the cutting edges, I provide fins which serve to prevent stones or gravel interfering with the free movement of the shank.

Other objects and advantages of the invention will hereinafter appear and the 45 novel features thereof will be particularly pointed out in the appended claims.

The invention is clearly illustrated in the

accompanying drawings, which, with the numerals of reference marked thereon, form a part of this specification, and in which— 55

Figure 1 is a plan view of my improved anchor, with the shank broken away.

Fig. 2 is a side elevation thereof.

Fig. 3 is a rear end view.

Fig. 4 is an end view of one of the flukes. 60

Fig. 5 is a side view of the outer end of one of the flukes.

Fig. 6 is a detail in side elevation of the pivot-end of the shank. 65

Fig. 7 is an edge view thereof.

Like numerals of reference indicate like parts throughout the several views.

Referring to the drawings,

1 designates the head from which project the flukes 2 of considerable length. The 70 head 1 is provided with a plurality of openings 3, which may be of any desired form, for the purpose of permitting the passage of the water so as to offer the least resistance to the movement of the ship when being 75 driven into a heavy sea.

The forward side of the head is provided with webs with cutting edges 4, 4 which also serve to reinforce the flukes at their connection with the head, and between these 80 cutting edges is an opening 5 in which is received the head of the shank 6. As seen most clearly in Fig. 1, this opening is of greater lateral dimension than that of the shank so as to provide sufficient space to 85 allow of the requisite lateral movement of the shank and to prevent freezing or clogging at this point, and on each side of this opening at the inner sides of these cutting edges are the fins 7, which prevent the entrance 90 of small particles, as stones and gravel, between said shank and the walls of the cutting edges.

The shank is provided with the usual trunnion or pivot pin 8, as seen clearly in 95 Figs. 6 and 7, which is received within the depression 9 in the head and upon which pin the shank turns as upon a pivot in the usual manner.

10 is a locking pin disposed at right angles 100 to the pivot pin 8, as seen in Fig. 3, holding the shank in the head and preventing displacement thereof, yet giving it the requisite freedom of movement.

The flukes 2 are in general contour in the form of a triangle in cross section. At their points, upon their inner faces, they are inclined outwardly, as at 11, at a greater 5 or less angle, the inner faces 12 being substantially perpendicular. These flukes are oppositely beveled, as seen at 13 and 14, Fig. 4, so that, when they are forced laterally by unequal resistances on the inclined 10 faces 11, due to one inclined face being lower in the bottom than the other, the lower fluke moving laterally will also rise on its lower beveled face until both flukes are at the same level in the bottom, or in other words, 15 until the resistances on the faces 11 are equal.

In use, when the anchor strikes the sea bottom, if one fluke should be drawn into the sea bottom deeper than the other it at 20 once commences to travel in a side motion, by reason of the vertical face 11 offering more resistance, which causes it to slide up from the angle on the under side of the fluke, forcing the sand upward, bringing 25 the anchor into a horizontal position. Now, if the other fluke becomes more deeply embedded, the reverse motion takes place with the result that the anchor is again brought into its horizontal position. When this anchor is embedded in the sea bottom with one fluke deeper than the other and a strain is exerted on the cable sufficient to drag 30 the anchor, the fluke which is lowest embedded is crowded by the bevel 11 to move 35 the anchor from said bevel which causes said fluke to be crowded toward the surface by riding up on either the bevel 13 or 14, as the case may be, until the fluke on the opposite side exerts the same effect which 40 causes the flukes to always seek and retain the horizontal.

It is to be noted that the flukes are thicker on the inner side, that is the side nearest the shank, than on the outer side.

45 Furthermore, the flukes are drawn downward deeper and deeper into the sea bottom. The cutting edges not only cut into the sea bottom and tend to draw the anchor down, but they also afford resisting 50 surfaces in addition to reinforcing the connection between the flukes and the head of the anchor.

The space between the fins 7, as well as the concavity in the head, allows of material 55 lateral play, as well as play in a vertical direction and the transverse locking pin 10 has considerable play in the direction of the length of the head of the anchor, thus per-

mitting practically universal movement of the flukes with relation to the shank. 60

Modifications in detail may be resorted to without departing from the spirit of the invention or sacrificing any of its advantages.

What is claimed as new is:— 65

1. An anchor having flukes thicker on their inner faces than on their outer sides, and a web extending inwardly from a fluke and having a cutting edge.

2. An anchor having flukes thicker on 70 their inner sides than on the outer sides, with the inner faces of their outer ends outwardly beveled.

3. An anchor provided with flukes having their inner faces adjacent the ends outwardly inclined, and the lateral faces converging. 75

4. An anchor provided with flukes having the inner faces adjacent the ends outwardly inclined and the lateral faces converging, 80 a head carrying said flukes, and a shank loosely mounted in said head.

5. An anchor comprising a head with flukes having their inner faces outwardly inclined at their outer ends and webs having 85 cutting edges between the flukes, and a shank pivotally mounted in the head and having freedom of movement between the cutting edges both vertically and laterally.

6. An anchor comprising a head with 90 flukes and webs having cutting edges between the flukes, and a shank pivotally mounted in the head and having freedom of movement between the cutting edges both vertically and laterally, and also longitudinally in the head. 95

7. An anchor having a head and flukes, webs with cutting edges between the flukes with an opening between the cutting edges, said head having a concavity, a shank loosely received within said opening and having a transverse member in said concavity, and a locking member passed through the head and permitting limited play of said transverse member. 100

8. An anchor having spaced-apart webs with cutting edges between its flukes, with fins upon opposite sides of the opening between the cutting edges. 105

In testimony whereof I affix my signature 110 in the presence of two witnesses.

ALBERT F. EELLS.
